(57) **CLAIM**

The ornamental design for a bottle container, as shown and described.

DESCRIPTION

FIG. 1 is a front perspective view of a bottle container showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is another perspective view thereof, with the bottle pump engaged; and,

FIG. 9 is another perspective view thereof, with the container cover engaged.

The dotted line showing of the bottle pump and the container cover are for illustrative purposes only and forms no part of the claimed design.
